UNITED STATES PATENT OFFICE.

FERNANDO J. LE BEAU, OF CHICAGO, ILLINOIS, ASSIGNOR OF ONE-HALF TO FREDERICK LUNDIN, OF CHICAGO, ILLINOIS.

EMERGENCY-LOCK.

1,254,194.

Specification of Letters Patent. Patented Jan. 22, 1918.

Application filed March 12, 1917. Serial No. 154,143.

To all whom it may concern:

Be it known that I, FERNANDO J. LE BEAU, a citizen of the United States, residing at Chicago, in the county of Cook and State of Illinois, have invented a certain new and useful Improvement in Emergency-Locks, of which the following is a specification.

While many of the features of this invention are applicable to locks generally, it is so specially applicable to emergency exit doors of the general type shown in Freed Patent, Number 992,554, issued May 16th, 1911, that it is so entitled and described.

15 The object of this invention is to provide a door latch operable by knobs on opposite sides of the door with a locking device for detachably securing one of the knobs against rotation to operate the latch in 20 which any of the standard forms or makes of tumbler locks can be substituted in the mechanism at the will of the purchaser, thus doing away with the requirements that the contractor for the latch mechanism be 25 also the contractor for the lock mechanism.

The invention consists in mechanism for carrying out the foregoing objects, which can be easily and cheaply made and installed, which is satisfactory in operation, 30 and is not readily liable to get out of order. The invention consists more particularly in the features and details of construction which will be hereafter more fully set forth in the specification and claims.

35 Referring to the drawings, in which similar numerals indicate the same parts throughout the several views,

Fig. 1 is a side view of the mechanism of this invention in the position intended to be adopted in the room with the door in its closed

position, as shown in Fig. 1.

Fig. 2 is a side view of the mechanism in the position intended to be adopted in the room with the door in its closed position, as shown in Fig. 2.

Fig. 3 is a enlarged perspective view of the parts of Fig. 2, showing a detail of the latch member in its closed position.

Fig. 4 is a front elevation of the mechanism of Fig. 1.

Fig. 5 is a plan view of the latch member, showing its parts, as shown in Fig. 4.

Fig. 6 is a side view of the mechanism of Fig. 1.

Fig. 7 is a side view of the mechanism of Fig. 1.

view of so much of the mechanism as appears in Fig. 7, taken at right angles to Fig. 7.

The emergency exit door to which the device is applied comprises a vertical rear plate 10 located on the outside of the room from which emergency exit is to be effected, and a front plate 12 movable with reference thereto normally pushed outward by springs 14 inclosing telescoping rods 16 in the ordinary manner, the front plate being retained in normal position by a marginal flange 18 located upon the edge member 20 of the door. In the particular illustration in the drawings, members 10, 20 and 18 are made all in one piece.

The door is mounted by mechanism not shown in the drawings to swing from closed position adjacent to the door frame 22 to an open position so that persons can pass through the door opening closed by the door. The door is held in the position shown in the figures by a sliding latch device mounted, for convenience, on a small plate 23 secured on rear wall 10 of the door, though all the mechanism hereafter described as mounted on plate 23 may be mounted directly on wall 10 without departing from this invention. The latch device essentially comprises a U-shaped carriage 24 in which a pivoted latch member 26 is mounted. The sliding motion of the carriage is made possible by the fact that it is provided on opposite sides with angular flanges 28 which embrace rods 30 mounted upon fixed supports 32 rising from the back plate 10, these rods being equipped with

spings 34 having a free end which is secured to the carriage 24 and which is held in place by a lock washer 36.

Fig. 1 is a side view of the mechanism in the position intended to be adopted in the room with the door in its closed position, as shown in Fig. 1.

Fig. 2 is a side view of the mechanism in the position intended to be adopted in the room with the door in its closed position, as shown in Fig. 2.

Fig. 3 is a enlarged perspective view of the parts of Fig. 2, showing a detail of the latch member in its closed position.

Fig. 4 is a front elevation of the mechanism of Fig. 1.

Fig. 5 is a plan view of the latch member, showing its parts, as shown in Fig. 4.

Fig. 6 is a side view of the mechanism of Fig. 1.

Fig. 7 is a side view of the mechanism of Fig. 1.

the door when the door is open and is approaching closed position; that is to say, when the door approaches closed position, the inclined edge 44 of latch dog 26 strikes the edge of the door frame 22, with the result that the carriage 24 and latch dog 26 are, as the door closes, moved bodily to the left as viewed in the figures against the action of springs 34 until such time as the 10 parts reach the position of, say, Fig. 6, whereupon the springs force the carriage and latch to the right so that latch dog 26 enters recess 46 in the door frame and the door becomes locked. The latch mechanism 15 described in this paragraph is more fully described and claimed in my companion application, Serial Number 152,982.

For all practical purposes, the carriage 24 and attached parts thus described constitute 20 a rigid locking bolt, and they will, for convenience, be sometimes so referred to hereafter. Other forms of spring pressed rigid locking bolts may be substituted in the mechanism which follows without departing from 25 this invention.

The latch mechanism just described standing alone can be released from latched position by pressure upon the plate 12 in the manner described, and cannot be released in 30 any other manner from the front side of the door (the side of plate 12), and cannot be in any manner released from the opposite side of the door. While doors so constructed are useful, it is frequently desirable to 35 equip doors with rotatable door-knobs of the ordinary type, putting one on the inside of the door which can be always rotated by a person desiring to open the door, and putting another on the outside of the door 40 which is controlled by a lock mechanism proper rendering it operative or inoperative at the will of the key holder for moving the latch bolt mechanism from the outside of the door.

45 In the drawings, inner knob 50 and outer knob 52 are provided, each respectively equipped with shafts 54 and 56 entering the door and rotatively telescoping together at 58. Rigidly connected to shaft 54 is a metallic disk 60 having three outwardly turned lugs 62 arranged on the circumference of a circle so that they are adapted to bear and rotate in a circular hole 64 formed in an internal frame plate 66 supported upon plate 50 55 23 by legs 68 and screws 70. Similarly, shaft 56 has rigidly attached to it a disk 72 having outwardly turned lugs 74 arranged in the circumference of a circle so that they take bearing and rotate in a circular hole 76 formed in plate 23. As shown, particularly in Fig. 5, the disks 60 and 72 are a substantial distance apart so that there is room between them for a lever 78, one of whose ends 79 is pivoted in a supporting 60 lug 80 near the bottom of plate 23, and

whose upper end 82 bears against a lug 83 upon the side of the carriage 24; the result being that the springs 34 through the action of the carriage normally tend to move lever 78 to the right until it reaches the position 70 shown in Fig. 3.

In the central portion of lever 78 is formed an enlargement 84 containing an elongated transverse recess 86 within which the shafts 54—56 lie. This recess 86 is of 75 such a size and shape that the lever 78 may move between the positions of Figs. 3 and 4 without in any way being interfered with by these shafts.

Extending from disk 60 and away from 80 support 66 are two lugs 88 and 90 arranged to embrace the enlargement 84 on lever 78 in such a way that rotation of handle 50 in either direction will always positively move lever 78 and consequently latch mechanism 85 24—26.

In a similar manner, disk 72 is provided with corresponding lugs 92 and 94 similarly embracing enlargement 84 on lever 78, enabling similar control of lever 78 by knob 90 52 under all conditions, except when knob 52 is locked against movement in the manner hereafter described. Lugs 92 and 94 are so placed on disk 72 that when knob 52 is locked, as hereafter described, these lugs 95 92 and 94 do not in any way prevent the operation of lever 78 under manipulation of knob 50.

Lug 94, heretofore described, is different 100 in form from lug 90 in that it is provided with a downwardly extending finger 96 adapted to enter a notch or recess 98 formed in member 100 of a locking plate 102 slidingly mounted to move parallel with reference to plate 23. In the particular case 105 here illustrated, this locking plate 102 is mounted for reciprocation by having one end member 100 perforated to receive an extending tongue 104 on frame plate 66, and its opposite end 106 is similarly perforated 110 to receive a corresponding tongue 108 on another frame plate 110 supported by lug 80 and lug 112 secured to plate 23 by screws 114. The parts are so arranged that when locking plate 102 is in the position shown in 115 Fig. 8, finger 96 is in notch 98 and is held rigid in that position, with the result that knob 52 cannot turn and consequently cannot operate the latch mechanism; while, on the other hand, when locking plate 102 120 drops or is moved to the position of Fig. 2, the locking plate and all of its parts entirely clear finger 96, with the result that rotation of knob 52 operates lever 78 in either direction, and consequently the latch mechanism, thus enabling a person approaching the door from the outside to secure admission to the room by simply rotating knob 52 in the ordinary manner.

In order to detachably secure locking 130

plate 102 in each of the last two described positions at the will of the owner of the room controlled by the door, and to do this without its being necessary for the maker 5 of the parts thus far described to manufacture or contract for the key-operating lock proper, the parts are arranged of such a size and shape that any one of the standard lock cylinders; for instance those made by Yale, 10 Corbin, and similar concerns, may be inserted in position to operate member 102 without otherwise disturbing the parts heretofore described. In the drawings, one of the standard cylinders 116 provided with a 15 key 118 is inserted in the position shown so that the crank pin 120 on the standard crank arm 122 of such a device enters and travels in cam slot 124 so shaped and arranged, as shown, that rotation of the key 20 118 in the ordinary manner will reciprocate plate 102 between the locked and unlocked positions heretofore described, and the cam slot is also so shaped that at the end of the stroke of the key in either direction the 25 plate 102 cannot reciprocate without the assistance of the key; in other words, it is impossible, by taking hold of the plate 102, to operate the lock mechanism 116.

Having thus described my invention, 30 what I claim as new and desire to secure by Letters Patent, is:—

1. A device of the class described, in combination, a suitable support, a latch mechanism, a lever pivoted a distance from the 35 latch mechanism and engaging the latch mechanism to operate it, an enlargement upon said lever provided with an elongated slot extending transversely thereof, a pivoted operating shaft so located as to extend 40 through said elongated slot in the lever, and means carried by said shaft engaging the enlargement of the lever, so placed that rotating the shaft in either direction will correspondingly rock the lever.

45 2. A device of the class described, in combination, a suitable support, a latch mechanism, a lever pivoted a distance from the latch mechanism and engaging the latch mechanism to operate it, an enlargement 50 upon said lever provided with an elongated slot extending transversely thereof, a pivoted operating shaft so located as to extend through said elongated slot in the lever, and means carried by said shaft engaging 55 the enlargement of the lever, so placed that rotating the shaft in either direction will correspondingly rock the lever, said engaging means being also so located that the lever may be rocked entirely independently of 60 said lugs and the shaft connected therewith.

3. A device of the class described, in combination, a suitable support, a latch mechanism, a lever pivoted a distance from the 65 latch mechanism and engaging the latch

mechanism to operate it, an enlargement upon said lever provided with an elongated slot extending transversely thereof, a pivoted operating shaft so located as to extend through said elongated slot in the lever, 70 means carried by said shaft engaging the enlargement of the lever, so placed that rotating the shaft in either direction will correspondingly rock the lever, said engaging means being also so located that the lever 75 may be rocked entirely independently of said engaging means and the shaft connected therewith, and a key-controlled locking device adapted to secure said shaft without interfering with movement of the lever. 80

4. A device of the class described, in combination, a suitable support, a latch mechanism, a lever pivoted a distance from the latch mechanism and engaging the latch mechanism to operate it, an enlargement 85 upon said lever provided with an elongated slot extending transversely thereof, a pivoted operating shaft so located as to extend through said elongated slot in the lever, and lugs carried by said shaft embracing the 90 outside of the enlargement of the lever, so placed that rotating the shaft in either direction will correspondingly rock the lever.

5. In a device of the class described, in combination, a suitable support, a latch 95 mechanism, a lever pivoted a distance from the latch mechanism and engaging the latch mechanism to operate it, an enlargement upon said lever provided with an elongated 100 slot extending transversely thereof, a pivoted operating shaft so located as to extend through said elongated slot in the lever, and lugs carried by said shaft embracing the outside of the enlargement of the lever, so placed that rotating the shaft in either direction 105 will correspondingly rock the lever, said lugs being also so located that the lever may be rocked entirely independently of said lugs and the shaft connected therewith.

6. In a device of the class described, in combination, a suitable support, a latch mechanism, a lever pivoted a distance from the latch mechanism and engaging the latch mechanism to operate it, an enlargement 110 upon said lever provided with an elongated slot extending transversely thereof, a pivoted operating shaft so located as to extend through said elongated slot in the lever, lugs carried by said shaft embracing the 115 outside of the enlargement of the lever, so placed that rotating the shaft in either direction will correspondingly rock the lever, said lugs being also so located that the lever may be rocked entirely independently of 120 said lugs and the shaft connected therewith, and a key-controlled locking device adapted 125 to secure said lugs and shaft without interfering with movement of the lever.

7. In a device of the class described, in combination with a door and its door frame, 130

a latch mechanism spring pressed outward from the door and engaging the door frame, a lever pivoted inside the door and having its free end engaging the latch to operate it against its spring mechanism, a pair of door knobs located on opposite sides of the door, means by which each door knob may independently move said lever, a projecting finger carried by one door knob mechanism, a reciprocatable locking plate adapted to move between two different positions; in one of which it engages said finger and in the other

of which it clears it, and an independent key controlled lock mechanism adapted to detachably secure said locking plate in each of its said positions.

In witness whereof, I have hereunto subscribed my name in the presence of two witnesses.

FERNANDO J. LE BEAU.
